Primary Examiner — Jae Liang(74) *Attorney, Agent, or Firm* — Gottlieb, Rackman & Reisman, P.C.(57) **CLAIM**

The ornamental design for a vessel, as shown and described.

DESCRIPTION

FIG. 1 is a perspective view of a vessel showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The vessel is shown with a symbolic break in its length. The appearance of any portion of the article between the break lines forms no part of the claimed design.
